BASKET COVER

Kyffin T. Bussard, Albany, Oreg.; Ward Ruthruff, executor of said Kyffin T. Bussard, deceased, assignor to R. D. Bussard, Albany, Oreg.

Application July 21, 1950, Serial No. 175,233

3 Claims. (Cl. 160—354)

1

This invention relates to improvements in a basket cover.

An object of this invention is to provide an improvement in the art of dry cleaning by supplying an improved cover for the whirling tub used to extract liquid from the material being cleaned, thereby preventing the material, as clothing, from creeping through the normally open top of the basket.

Another object of this invention is to provide an improved cover which is expansible to a predetermined maximum width or diameter by means of a resilient stiffener which forms a part of the cover and which is so arranged as to be easily pulled together to remove the cover from the whirling tub.

Ancillary objects and features of importance will become apparent in following the description of the illustrated form of the invention.

In the drawings:

Figure 1 is a longitudinal sectional view of the improved cover showing its use in connection with a substantially conventional extractor tub and extractor basket;

Figure 2 is a perspective view of the cover;

Figure 3 is a plan view of the resilient wire which is employed as a stiffener in the cover; and

Figure 4 is an enlarged detail view taken substantially on the line 4—4 of Figure 2 and in the direction of the arrows.

The cover to be described is designed and intended primarily to be used in the laundry and dry cleaning art as a cover or retainer for the open end of the extractor tub 10. This tub is foraminous, being provided with a number of openings 12 therein through which the liquid of the garments 14 is adapted to pass when the tub is rotated at a rather high speed through the spindle drive assembly 16. The extractor basket 18 is disposed therearound, also carried by the assembly 16. Said basket is supplied with an opening 20 at the top thereof, while the tub is provided with an opening 22 at the top thereof, which opening is defined by the rolled upper edge 24 of said tub 10.

The cover 26 (Figure 2) consists of at least two thicknesses 28 and 30 of material, as canvas or duck connected together by transverse rows 32 and longitudinal rows 34 of stitching. An arcuate row 36 of stitching is provided adjacent the periphery of the cover and at the ends of the transverse and longitudinal rows of stitching. A circular row 38 of stitching is provided closer to the periphery of the cover and provides, with the row 36, a pocket 40 in which is disposed the resilient stiffener assembly 42 (Figure 4).

2

This stiffener assembly consists of a flexible tube 44 having the ends 46 and 48 of the wire 50 disposed therein. The wire forms one complete coil and a part of another before the ends thereof are disposed slidably in the tube 44. Accordingly by pulling opposite sides of the cover 26 together, the ends 46 and 48 will slide in the tube 44, thereby effectively decreasing the diameter or width of the cover so that it may be inserted below the rolled edge 24 of the tub 10. As soon as the pulling force on the cover is relaxed, it will automatically spring to the condition disclosed in Figure 1, that is, to the condition to close the opening 22.

15 For strengthening purposes, one or more screw and washer assemblies 56 may pass through the thicknesses 28 and 30 of material and the strap 58 which is stitched over the pocket 40 may be used for the same purpose. There is a tendency for the wire 50 to creep so as to become disengaged from the tube or coil spring 44. To prevent this, the spaced flanges 60 on the wire 50 are contacted by the edges of the strap 58, and thus the wire cannot creep.

20 16 A strap 61 which is stitched at 62 and 64 adjacent the ends thereof to the thicknesses of material is disposed on one surface of the material of the cover. This strap is stitched also at 66, which is substantially the center of the strap, to thereby provide two hand holding loops 68 and 70.

25 In operation, the loops 68 and 70 may be grasped both to insert and to remove the cover 26 from the whirling tub.

Having described the invention, what is claimed as new is:

30 1. For use with an extractor tub, a flexible cover having a peripheral pocket extending entirely therearound, a resilient wire carried within said pocket and having its ends overlapped, a stiffening tube disposed within said pocket and having its ends circumferentially spaced from one another, the overlapping ends of said wire being disposed within the ends of said tube whereby the tube and wire constitute a yieldable means 40 to expand and reduce the effective covering surface of the cover.

35 2. For use with an extractor tub, a flexible cover having a peripheral pocket extending entirely therearound, a resilient wire carried within said pocket and having its ends overlapped, a stiffening tube disposed within said pocket and having its ends circumferentially spaced from one another, the overlapping ends of said wire being disposed within the ends of said tube whereby the tube and wire constitute a yieldable means 45 to expand and reduce the effective covering

ing surface of the cover, said cover being comprised of two thicknesses of material and said pocket being formed therebetween.

3. The combination of claim 2 and a strap having a loop and fastened to said cover, said wire being passed through the loop of said strap, and means fixed to said wire in spaced relationship to each other and on opposite sides of the loop of said strap to abut opposite edges of the strap thereby forming stops to prevent said wire from 10 creeping.

KYFFIN T. BUSSARD.
